SINGLE-TRIGGER DOUBLE-BARREL FIREARM

Joseph A. Morrone, Westerly, R. I.

Application March 8, 1949, Serial No. 80,173

7 Claims. (Cl. 42—42)

1

This invention is directed to certain improvements in firearms and more particularly to firearms of the over and under type in which a single trigger of the non-selective type is employed to fire the barrels.

The object of my invention is to materially simplify the construction of a firearm of this type and to employ a novel combination of elements for positively controlling the firing of the barrels.

A further object is to provide a combination of elements which eliminates inertia means for automatically locking the firing mechanism.

A practical embodiment of my invention is represented in the accompanying drawings, in which

Fig. 1 represents a detail side view of the firearm, partly in section.

Fig. 2 represents a side view of the firearm "broken," part of the stock being broken away.

Fig. 3 represents a detail longitudinal vertical section taken in a longitudinal vertical plane between the hammers.

Fig. 4 represents an enlarged detail longitudinal vertical section showing the hammers in fired position.

Fig. 5 represents an end view of the elements shown in Fig. 4.

Fig. 6 represents a detail bottom plan view of the top lever.

Fig. 7 represents a detail cross section of the spring tension for the top lever.

Fig. 8 represents a top plan view of the kick block.

Fig. 9 represents a detail side view of the trunnion block and barrels.

Fig. 10 represents a rear end view of the same.

Fig. 11 represents a top plan view of the firing mechanism.

Fig. 12 represents a detail side view of the trigger plate.

Fig. 13 represents a plan view of the short sear for controlling the operation of the long hammer.

Fig. 14 represents a side view of the same.

Fig. 15 represents a plan view of the long sear for controlling the operation of the short hammer.

Fig. 16 represents a side view of the same.

Fig. 17 represents an end view of the sear tripping rock lever.

Fig. 18 represents a side view of the same.

Fig. 19 represents a side view of the single trigger.

Fig. 20 represents an end view of the same.

2

Fig. 21 represents a detail cross section showing connection between the shank of top lever and breech locking pin.

Fig. 22 represents a side view of the frame including the receiver, breech block and tang.

Fig. 23 represents a front end view of the same.

Fig. 24 represents a rear end view of the same.

Fig. 25 represents a top plan view of the same.

The lower and upper barrels of the firearm 10 are denoted by 1 and 2, the trunnion block in which the rear ends of the barrels are secured, by 3, its trunnions by 4 and the fore-end by 5.

The stock is denoted by 6. The frame which together with the trigger plate carries the firing mechanism, includes the breech block 7, the forwardly extended receiver 8 to which is pivoted the trunnion block 3, and the rearwardly extended top tang 9. The removable trigger plate 10 is provided with uprising sides 11 and also with an uprising rear end 12. This trigger plate may be removably secured at its forward end to the breech block 7 of the frame by a screw 13 and the uprising rear end 12 may be secured to the rear end of the tang 9 of the frame by a screw 14.

A screw bolt 15 which extends forwardly through the stock 6 into engagement with the uprising rear end 12 of the trigger plate 10 serves to secure the frame and trigger plate within the recessed forward end of the stock 6. The trunnion block 3 with its superposed barrels 1 and 2 may be releasably locked to the breech block 7 of the frame when the firearm is closed, by the usual laterally swinging top lever 16, the vertical shank 17 of which is rotatably mounted in the breech block 7. This shank 17 is provided with the cross pin 18 for operating the sliding lock pin 19 whose forward end is arranged to enter the recess 20 in the rear face of the trunnion block 3. This shank 17 is provided with cross holes 21 and 22 through which the lower and upper firing pins 23 and 24 pass. The top lever 16 is yieldingly held in its locking position by the use of a spring biased pin 25 working in a flat V-shaped recess in the lever shank 17 (see Fig. 7). These firing pins are slidably mounted in the breech block 7 of the frame and they are located in the same longitudinal vertical plane. Springs 26 and 27 are provided for yieldingly holding the firing pins 23 and 24 in their retracted positions.

The firing pins 23 and 24 are shown as angularly disposed, the lower firing pin 23 being inclined from its forward end rearwardly and upwardly, and upper firing pin 24 being inclined

from its forward end rearwardly and downwardly. Pins 23 and 24 are located at different angles to the horizontal longitudinal axis of breech block 7 as shown in Fig. 4.

The short hammer 28 and the long hammer 29 for firing the lower and upper barrels 1 and 2 respectively, are pivoted on a cross pin 30 fixedly mounted in the uprising sides 11 of the removable trigger plate 10. These hammers have overlapping firing pin striking surfaces on inwardly projected lower and upper lugs 31 and 32 which are located in the same longitudinal vertical plane as the firing pins 23 and 24 and at different distances from the pivot pin 30. A spacer 33 is interposed between the hammers on the pivot pin 30.

The usual main springs 34 and 35 operate to bias the hammers 28 and 29 in a forward direction for striking their respective firing pins 23 and 24 when the hammers are successively released by their respective long and short sears 36 and 37. These hammer biasing springs 34 and 35 are shown as of the usual hair pin type with the rear ends of the springs engaging the trigger plate and the front ends of the springs seated in the recesses 38 and 39 of their respective hammers 28 and 29.

These sears 36 and 37 are pivoted on a cross pin 40 fixedly mounted in the said uprising sides 11 of the trigger plate 10. The long sear 36 for releasably locking the short hammer 28 for firing the lower barrel 1, when the hammer is in its cocked position, has its forward arm arranged to releasably engage an abutment 41 on the hub of the said hammer 28. The short sear 37 for releasably locking the long hammer 29 for firing the upper barrel 2, when the hammer is in its cocked position, has its forward arm arranged to releasably engage an abutment 42 on the hub of the said hammer 29.

The long and short sears 36 and 37 are biased to normally depress their rear arms, by coil springs 43 and 44 located between the trigger plate 10 and the front arms of said sears.

The single trigger 45 is pivoted on the cross pin 40 which serves also as a pivot for the long and short sears 36 and 37. This trigger 45 is biased forwardly by a coil spring 46 located between the trigger plate 10 and the front arm of the trigger.

A sear tripper is carried by the trigger 45, which tripper is shown as comprising a rock lever 47 pivoted at 48 to the top of the said trigger, a coil spring 49 being located between the trigger and the rear arm of the rock lever 47 serving to bias the lever to depress its front arm.

This sear tripping rock lever 47 is positively connected to the long sear 36 as, for instance, by providing an inverted L-shaped slot 50 in the rear arm of the rock lever 47 and a laterally projecting pin 51 on the rear arm of the long sear 36, which extends into said slot 50, the length of said slot not being critical.

The front arm of the rock lever 47 is preferably beveled in one direction and the rear arm of the short sear 37 is provided with a lateral extension 52, the edge of which is beveled in the opposite direction for facilitating the coaction of the rock lever and short sear 37 as will be hereinafter explained.

The means for locking the trigger 45 is shown as comprising the following elements. The trigger is provided with an uprising rear end 53 arranged in position to be engaged by the depending arm 54 of a slidable safety lock 55 when the

lock is slid rearwardly along the tang 9 of the frame.

The fore-end 5 may be removably secured in position, as, for instance, by providing the fore-end iron 56 with a spring pressed plunger 57 arranged in position to engage a recessed stud 58 depending from a clip 59, said stud projecting into the recess 60 in the said fore-end iron.

The breaking of the firearm may be assisted by the following means. A kick block 61 is provided with a nose 62 located under the rear end of the trunnion block 3. This kick block is pressed upward by a spring 63 and it is provided with a tongue 64 which is adapted to enter a groove 65 in the bottom of the shank 17 when the lock lever 16 is swung into position to release the trunnion block 3 by withdrawing the locking pin 19. The spring 63 will tend to push the kick block upwardly and thus exert an upward pressure on the trunnion block 3.

The hammer cocking means which operates as the firearm is broken, is shown as comprising the following elements. Two cocking pins 66 and 67 are slidable in the frame through the receiver and breech block with the front ends of the cocking pins engaged by two concave cam surfaces 68 and 69 in the rear end of the fore-end iron 56, the rear ends of these cocking pins engaging the offset cams 70 and 71 on the hammers 28 and 29.

The shell extractor mechanism is shown as including the following elements. The shank 12 of the extractor 73 is slidable in the undercut groove 74 extending along one side of the trunnion block 3 and this shank is provided with an abutment 75 which is located in position to be engaged by the fore-end iron 56 to move the extractor rearwardly as the firearm is broken. The closing of the firearm will cause the extractor to be returned to its normal position.

The operation of the firing mechanism is as follows. The trigger 45 is first unlocked by the sliding forward of the safety lock 55. The trigger 45 is then pulled back against the compression of its spring 46. This rocking movement of the trigger will raise the rock lever 47 pivoted to the top of the trigger and carried thereby and, consequently, impart this upward motion to the rear end of long sear 36 due to the riding engagement of its laterally projecting pin 51 with the forward bottom section of L-shaped slot 50 in rock lever 47. Long sear 36 is thus rocked on its pivot pin 40 thereby depressing its front end until the same is released from its locking engagement with abutment 41 on the hub of short hammer 28. Hammer 28 will then be rocked forwardly by its main spring 34 to cause lug 31 to strike lower firing pin 33 and fire the lower barrel 1.

To fire the upper barrel 2, the pull on the trigger 45, which has just fired lower barrel 1 as above described, must be released and the trigger returned to its forward position. This return is accomplished by the pressure of spring 48 against the under side of trigger 45 causing the latter to swing forwardly downward on cross pin 40. As the trigger so swings forwardly and downwardly its rear end is lowered carrying with it the rock lever 47 swung thereon at 48. As the pressure on trigger 45 is further released this lessens the upward pressure on the lower surface of slot 50 on pin 51 so that spring 49 overcomes the inertia of and is permitted to urge the rear end of rock lever 47 upwardly due to its pivot at 48, with a consequent downward motion of the rock lever front arm; pin 51, meanwhile, riding in L-shaped slot 50. It will be noted that the

rear end of long sear 36 stays in its raised position since its forward end is held beneath the hammer 28 after the latter has been urged forward by its spring 34. The tilting downwardly of the front arm of lever 47 due to the action of spring 49, slightly precedes the completion of the forward carry of lever 47 induced by the swing of trigger 45 carrying the lever pivot 48, said trigger being urged by spring 46 as above set forth. At the end of said forward carry the front arm of lever 47 rests beneath the rear arm of short sear 37.

Trigger 45 may now be pulled again which will discharge upper barrel 2 involving mechanism functioning as follows: The trigger as it is pulled swings about pin 40 in an arc rearwardly and upwardly. Due to the shape of slot 50 in rock lever 47 permitting pin 51 to ride free therein, the front arm of said lever 47 will engage the under side of the tail of sear 37 before the rock lever starts to rock rearwardly on pivot 48. This rocking is influenced by several factors as the trigger pull continues including the pin 51 which is fixed in its highest position contacting the upper side of slot 50 due to the arc described by lever 47 when lifted by the trigger 45 pulled as above set forth, and partially by the weight of lever 47 in its unbalanced relation to pivot 48, which position tends to compress spring 49. Front arm of lever 47 is positioned under the tail of sear 37, while pivot 48 is being raised, pin 51 being fixed against downward motion as above described. The continued lift of lever 47 by the continuing pressure on trigger 45 carries the rock lever front arm, which is in contact with or beneath sear rear arm 37, upwardly and lifts the latter, rocks lever 48 to the rear thereby raising the tail of sear 37 to a point where its depressed arm is released from its locking engagement with the abutment 42 on the hub of long hammer 29. This hammer 29 will then be urged forward by its main spring 35 to cause its lug 32 to strike the upper firing pin 24 and thereby fire said upper barrel 2.

It is evident that various changes may be resorted to in the construction, form and arrangement of the several parts without departing from the spirit and scope of my invention, and hence I do not intend to be limited to the particular embodiment herein shown and described.

What I claim is:

1. In a firearm, a frame, two spring biased hammers, means for cocking them, two spring biased rocking sears for releasably holding the hammers cocked, a trigger, a spring biased rock lever thereon, and a pin and slot connection between the lever and one sear to trip it to release one hammer when the trigger is pulled, said lever being moved into position to trip the other sear when the trigger is returned to its normal position and to release the other hammer when the trigger is again pulled.

2. In a firearm, a frame, two spring biased hammers, means for cocking them, two spring biased rocking sears for releasably holding the hammers cocked, a trigger and a spring biased rock lever thereon, the lever having a slot and one of the sears having a pin projecting into the slot whereby the sear is tripped to release the hammer when the trigger is pulled, said lever being moved into position to trip the other sear when the trigger is returned to its normal position and to release the other hammer when the trigger is again pulled.

3. In a firearm, a frame, two spring biased hammers, means for cocking them, two spring

biased rocking sears for releasably holding the hammers cocked, a trigger, and a spring biased rock lever thereon having an inverted L-shaped slot and one of the sears having a pin projecting into the slot whereby the sear is tripped to release the hammer when the trigger is pulled, said lever being moved into position to trip the other sear when the trigger is returned to its normal position and to release the other hammer when the trigger is again pulled.

4. In an over and under firearm, a frame, two spring retracted firing pins located in the same longitudinal vertical plane, two spring biased rocking hammers provided with pin striking surfaces located in the same longitudinal vertical plane as the firing pins and at different distances from the axis of rotation of the hammers, means for cocking the hammers, two spring biased rocking sears for releasably holding the hammers cocked, a trigger and a spring biased rock lever thereon positively connected to one sear to trip it for releasing one hammer when the trigger is pulled, said lever being moved into position to trip the other sear when the trigger is returned to its normal position and to release the other hammer when the trigger is again pulled.

5. In an over and under firearm, a frame, two spring retracted firing pins located therein in the same longitudinal vertical plane, the upper firing pin inclined rearwardly and downwardly and the lower firing pin inclined rearwardly and upwardly, two spring biased rocking hammers provided with pin striking surfaces located in the same longitudinal vertical plane as the firing pins and at different distances from the axis of rotation of the hammers, means for cocking the hammers, two spring biased rocking sears for releasably holding the hammers cocked, a trigger and a spring biased rock lever thereon positively connected to one sear to trip it for releasing one hammer when the trigger is pulled, said rock lever being moved into position to trip the other sear when the trigger is returned to its normal position and to release the other hammer when the trigger is again pulled.

6. In an over and under firearm, a frame, a trigger plate removably secured thereto, two spring retracted slidable firing pins located in the frame in the same longitudinal vertical plane,

50 two spring biased hammers pivoted to the trigger plate and provided with pin striking surfaces located in the same longitudinal vertical plane as the firing pins and at different distances from the axis of rotation of the hammers, means for cocking the hammers, two spring biased rocking sears pivoted on the trigger plate for releasably holding the hammers cocked, a trigger pivoted on the trigger plate and a spring biased rock lever on the trigger positively connected to one sear 60 to release one hammer when the trigger is pulled, said lever being moved into position to trip the other sear when the trigger is returned to its normal position and to release the other hammer when the trigger is again pulled.

65 7. In an over and under firearm, a frame, a trigger plate removably secured thereto, two spring retracted firing pins slidable in the frame and arranged in the same longitudinal vertical plane, two spring biased hammers pivoted to the trigger plate and having inwardly directed offset pin striking lugs arranged in the same longitudinal vertical plane as the firing pins, means for cocking the hammers, a spring biased trigger pivoted on the trigger plate, longer and shorter 70 sears pivoted on the trigger plate for releasably

holding the hammers cocked, and a sear tripping lever pivoted on the trigger and positively connected to the longer sear and movable into operative connection with the shorter sear.
